UNITED STATES PATENT OFFICE.

FOKKO H. G. BRANDT AND GEORGE K. KRELL, OF KANSAS CITY, MISSOURI.

ADJUSTABLE STRINGER-SUPPORT FOR SCAFFOLDS.

1,346,170.

Specification of Letters Patent. Patented July 13, 1920.

Application filed July 1, 1918. Serial No. 242,816.

To all whom it may concern:

Be it known that we, FOKKO H. G. BRANDT and GEORGE K. KRELL, subjects of the German Emperor, residing at Kansas City, in 5 the county of Jackson and State of Missouri, have invented certain new and useful Improvements in Adjustable Stringer-Supports for Scaffolds, of which the following is a specification.

10 This invention relates to adjustable stringer supports for scaffolds and the like, and our object is to produce a device of the character set forth by which stringers can be easily, quickly and reliably secured at the 15 desired height without the use of nails or screws and without defacing or otherwise injuring the stringer or necessitating the cutting of the stringer.

To this end the invention consists in certain 20 novel and useful features of construction and combinations of parts as herein-after described and claimed; and in order that it may be fully understood reference is to be had to the accompanying drawing, in 25 which:

Figure 1, is an elevational view of a part of the scaffold equipped with stringer securing devices embodying the invention, a stringer being shown in section.

30 Fig. 2, is an elevational view taken at right angles to that shown by Fig. 1.

Fig. 3, is a horizontal section taken on the line III—III of Fig. 2.

In the said drawing, 1 indicates an 35 upright of a scaffold or the like and 2 a stringer to be secured at the desired height against said upright.

3 is an angle bracket underlying and supporting and fitting against the face of the 40 stringer at the opposite side thereof from the upright, the lower arm of the bracket terminating in an arcuate portion 4 provided with perforated ears 5, and fitting against the upright, and to hold said bracket 45 in such position a U-bolt 6 fits around the upright and extends through the perforated ears 5 and is engaged at its ends by retaining nuts 7. The upper arm of the bracket is provided with a pair of horizontal ears 8 50 through which extends a pivot pin 9 engaged by a retaining cotter pin 10, and projecting outwardly from the lower ear 8 at one side of the center thereof is a stop lug 11 for engagement by a locking arm 12 pivotally attached at 13 to the forked arm 14

of an angle arm 16 pivoted on bolt 9 between ears 8, the said angle arm being provided at its free end with a plurality of teeth 17 for embedment in the stringer 2 at the opposite side of the same from the upright 1. When 60 the angle arm is swung to cause its teeth to engage the stringer, it is driven home to cause said teeth to be embedded in the stringer, being struck with a hammer or the like, and then the locking arm 12 is permitted to assume a vertical position adjacent stop lug 11 so that it shall be impossible for the angle arm to swing or work outward and become disengaged from the stringer. To accomplish this disengagement the locking 70 arm must first be swung to a horizontal position above the plane of the upper side of stop lug 11, after which the angle arm can be forced outward by means of a suitable pry, until the stringer is free to be lifted or 75 slid longitudinally from the support.

From the above description it will be apparent that the appliance embodies the features of advantage enumerated as desirable in the statement of the object of the invention, and can be changed in form, proportion, detail, construction and organization of parts without departing from the spirit and scope of the appended claims.

We claim:

1. The combination of an upright, an angle bracket secured to the upright, an angle arm movably carried by the bracket and adapted to hold a stringer upon the bracket and against said upright, and means movable with and independently of said angle arm for engaging the bracket to prevent disengaging action of the said arm.

2. The combination of an upright, an angle bracket secured to the upright, an angle arm movably carried by the bracket and adapted to hold a stringer upon the bracket and against said upright, a locking arm pivotally attached to the angle arm and adapted to hang downward therefrom, and a stop lug projecting from the bracket in the path of said locking arm when pendent, to prevent disengaging movement of the angle arm.

3. The combination of an upright, an angle bracket adjustably secured to the upright and provided with a pair of perforated horizontal ears and a lug projecting outwardly from the undermost of said ears, a horizontally arranged angle arm pivoted

between said ears and provided at its free end with a plurality of teeth for embedment in the stringer resting upon the angle bracket and fitting against said upright, and

5 a locking arm pivoted to the opposite end of said angle arm and adapted to hang downward therefrom adjacent said stop lug to

prevent disengaging pivoted action of said angle arm.

In testimony whereof we affix our signatures.

FOKKO H. G. BRANDT.
GEORGE K. KRELL.
